SEWING SPACER FOR BUTTONS

Edward K. Lane, Jr., Denver, Colo.

Application April 24, 1950, Serial No. 157,708

1 Claim. (Cl. 223—110)

1 This invention relates to a button spacer for dressmakers, tailors, and the like, and has for its principal object the provision of a simple and easily used device which can be placed beneath a button to hold the latter while it is being stitched to a garment, and which will automatically space the button away from the garment a distance proportionate to the size of the button.

In stitching buttons to clothing, it is customary to space the buttons away from the goods a distance sufficient to allow the buttoned flap to pass beneath the button without wrinkling or distorting the goods. Buttons are usually proportioned in size in accordance with the thickness of the goods; that is, small buttons such as used on shirts, blouses, etc., are spaced very close to the goods, while large buttons, such as used on top-coats, overcoats, and the like, are spaced relatively far from the goods. This improved button spacer will automatically space the buttons in accordance with their size without it being necessary to give any attention to the spacing.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of a button, illustrating it spaced from a garment;

Fig. 2 is a top view of the improved button spacer; and

Fig. 3 is a longitudinal section therethrough, taken on the line 3—3, Fig. 2.

The improved button spacer is preferably formed from some type of moldable product, such as molded plastic, hard rubber, or similar substance.

The improved spacer is formed to provide a concavity having a plurality of concentric, circular steps 10 indented in a circular spacing member 11. The concavity terminates in a circular thread opening 12 at the bottom, from which a side passage 13 leads to form a keyhole-like slot therein.

The maximum thickness of the spacer 11 is equal to the greatest space required between the goods and the largest button. The innermost step has a thickness equal to the spacing desired between the goods and the smallest conventional button.

An ear 14 projects outwardly from the side of

2 the spacer 11 opposite to the passage 13. The ear is provided with an opening 15 to facilitate a finger grip thereon and to provide means for hanging the spacer or for tying a tape thereto.

In Fig. 1 the goods of a typical garment are indicated at 16, a button is indicated at 17, and the thread holding the button in place is indicated at 18. In use, the spacer is placed on the goods 16 with the opening 12 over the position at which the button is to be stitched.

The button 17 is then placed in the stepped concavity of the spacer 11 and will automatically approach the goods 16 in proportion to the diameter of the button, for a smaller button will descend to a lower step 10 than a larger button. The button is then stitched in place by means of the thread 18, after which the spacer 11 may be removed and the thread wrapped, as indicated at 19, to maintain the button at the proper spacing.

It is desired to call attention to the fact that the plurality of circular, concentric steps 10 act to receive the peripheral edge of the button 17 so as to automatically center the button over the central thread opening 12.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A device for spacing buttons from garments while sewing the former in place, comprising: a spacing member adapted to be positioned beneath the button and provided with a sidewardly opening passage to allow the member to be withdrawn from beneath the button after the latter has been stitched in place, said member being provided with a button-receiving concavity in its upper face aligned with the sidewardly opening passage; and a plurality of concentric steps formed in said concavity for receiving the peripheral edge of the button.
